2,439,250

TRANSIT CONCRETE MIXER

Louis G. Hilkemeier, West Allis, Wis., assignor to
 Chain Belt Company, Milwaukee, Wis., a corporation of Wisconsin

Application December 27, 1943, Serial No. 515,834

7 Claims. (Cl. 259—161)

1

This invention pertains to a concrete mixer such as is provided with a rotatable mixing drum and an axial opening at one end for receiving and/or discharging materials. Where such mixers are provided with a non-rotatable charging hopper, some difficulty has been encountered in sealing the space around the opening in the drum.

In transit concrete mixers the concrete carried in the mixer drum often occupies more than half of the drum volume particularly where the drum is used as an "agitator" to haul previously mixed concrete, and even where the drum axis is inclined with a discharge opening at the higher end, it may nevertheless be important to seal the opening to prevent the concrete from escaping from the drum. Concrete being of a very abrasive nature quickly deteriorates materials which it comes in contact with, such as the wearing surface between rotating and non-rotating parts, and sealing means now in use have generally been unable to resist the action of the concrete for more than a short period of time.

It is an object of the present invention to provide an improved sealing ring for disposition in structures such as those described above, one which will more adequately seal the space between the moving parts and last longer in service than seals heretofore employed. A further object of the invention is to provide a sealing arrangement and a separate bearing journal arranged so that closer sealing contact is effected as wear occurs in other parts of the journal.

Another object of the invention is to provide improved means for mounting and supporting the hopper relative to the drum so as to maintain concentricity between the abutting surfaces of the drum and the hopper.

Still another object is to provide a concrete mixer having a charging mechanism and feeding means so supported with respect to the mixer drum that these parts will better withstand the abrasive action of the concrete than mixers heretofore employed.

With the foregoing and other objects in mind, the invention resides in the novel disposition and combination of elements as hereinafter described and as shown in an embodiment thereof illustrated in the accompanying drawings, in which:

Figure 1 is a side elevation partly in section, il-

2

lustrating the assembly of the hopper on the rear portion of the mixing drum;

Figure 2 is an enlarged section of the seal illustrated in Figure 2;

Figure 3 is a perspective view of the seal packing prior to its assembly in the hopper-drum structure.

Figure 4 is a section taken on the line 4—4 of Figure 1; and

Figure 5 is an end view of the shaft closure shown in Figure 4.

Although Figure 1 of the drawings illustrates only the rear portion of the mixer drum, reference may be made to my copending application Ser. No. 432,933 filed March 2, 1942, entitled "Concrete mixer water supply system," now Patent No. 2,360,344, for a more complete disclosure of the function and disposition of the mixing elements of the mixer drum of a transit concrete mixer. It is sufficient here to point out that while the drum rotates about its axis, the charging hopper is restrained against rotation in order that it may be held in upright, material-receiving position. In one of its aspects, the present invention is directed to prevent leakage through the space between the rotating drum and the non-rotating hopper.

In the embodiment shown in the drawing, the drum 11 carries a pilot shaft 12 extending through the charging opening 13 a sufficient distance to adequately support the hopper 14, the inner end of shaft 12 being securely retained in a pair of axially spaced bosses or hubs 15 securely mounted to the inside of the drum. Each hub 15 has an internal opening (which may be square in cross section), somewhat larger than shaft 12, the hub being welded to a washer or collar 16 which fits snugly around shaft 12 and holds it firm with respect thereto.

Extending radially on either side of the hubs and welded or otherwise integral therewith are spokes 17, the outer ends of which are slidably mounted in tubular brackets 18 having a bevelled end portion adapted to be welded to flanged portions 19 on the drum blades 20. The flanged or lip portion 19 of the drum blades form an obtuse angle with the lifting or web portion of the blades and extend just sufficiently beyond the inner side of the web portion to provide space for a fillet weld 19' as clearly illustrated in Figure 1. The

spokes on the two hubs 15 are at right angles to each other so as to support the shaft in two planes. The shaft is thus securely supported from all sides by a pair of axially spaced, supporting members and its alignment with the drum axis and the machined surface on the drum opening 13 is insured. This construction enables the following assembly operations to be performed:

While the drum is mounted on its fixture for welding, a supporting arbor which fits snugly within hubs 15 is mounted axially of the drum. Brackets 18 are then adjusted on the spokes until the bevelled end portion fits snugly against the blade flange 19. The brackets are next welded to the blades and a weld is also deposited between the spoke and the bracket as indicated at 21 to rigidly connect them together. As the drum cools following the various welding operations which are performed on the blades and on its shell, there is apt to occur distortion so as to make the hubs slightly eccentric with respect to the true axis. Shaft 12, which replaces the supporting arbor, the latter used only while mounting the hubs, is sufficiently smaller in diameter than the hubs to compensate for such eccentricity, and having been axially aligned in the drum 11, collars 16 are slit into position for welding to the hubs. Set screws extending through tapped holes 22 in each hub may be employed as a fixture for the shaft during welding and when welding is completed the set screws are removed and the shaft may be held from moving axially in the hubs by means of a through-bolt 22' extending through one of the hubs and the shaft 12. Should it be necessary to remove shaft 12, the through bolt is removed and collars 16, which are now integral with the hubs will form aligned openings for a replacement shaft and insure that the latter will be axially disposed in the drum when it is inserted through hubs 16.

Hopper 14 carries an internal sleeve 23 extending for substantially the full length of the hopper through its rear wall and the hopper is supported thereby. This sleeve is mounted on spaced bushings 24 each of which is protected against the entrance of abrasive material from the outside by means of packing rings 25. Grease may be supplied to the space between the shaft and the sleeve through a grease fitting 26 which extends from the under side of the sleeve and through the back wall 27 of the hopper adjacent thereto. Provision is made for taking up the packing at the inner end of the sleeve by a packing nut 28 threaded on the sleeve, said nut having a notched portion 29 which may be aligned with a locking bar 30 removably secured to the under side of the hopper sleeve. The sleeve may be protected and the weight of the hopper distributed over the sleeve by any suitable connecting or covering means such as the plates shown in U. S. Patent 2,265,751 issued December 9, 1941 to Charles F. Ball.

The rear packing may also be taken up by adjustment of bolts 31 extending through a plate 33 enclosing the outer end of shaft 12, said screws being threaded into a pair of ears 34 projecting from either side of a sleeve member 23, the latter serving as a housing for the packing gland 32 which encloses the shaft 12 with its inner end arranged to press against the rear packing ring 25. In this arrangement, which is best illustrated in Figure 4, plate 33 is provided with a centrally disposed opening 35 to vent air from the space between the end of shaft 12 and plate 33 during inward movement of the hopper on its supporting

shaft. Sleeve member 32 is welded or otherwise made integrally secure to plate 33 and therefore when bolts 31 are tightened drawing plate 33 toward the hopper, sleeve 34 moves to the left as shown in Figure 1 causing the rear packing 25 to tightly seal the space between the shaft and its tubular housing. Shoulders 36 on the inner side of tubular member 23 limit movement of bushings 24 toward each other, their movement away from each other being prevented by packing retaining means 28 and 33 respectively as previously described. Lubricant may be supplied to the space between packing rings 25 through suitable means such as grease fitting 26.

As illustrated in the drawings, the hopper is somewhat elbow-shaped and terminates in a lower portion which is substantially annular and somewhat smaller than the drum opening. This terminal portion of the hopper is spaced a distance axially outside the end of the drum and carries on it the sealing mechanism illustrated in more detail in Figure 2. Mechanism for sliding the hopper 14 back and forth on shaft 12 is illustrated only in outline, a pair of arms 37 being connected to trunnions 38 extending from either side of the hopper, said arms being pivoted about a shaft 39 mounted on the mixer frame and actuated by suitable means such as the hand wheel shown in the aforesaid Ball patent. When the hopper is slid back from the drum opening, a space is provided between the drum opening and the sealing mechanism for discharge of the mixed concrete from the drum, whereas, when the hopper is forced toward the drum, the sealing mechanism engages the end of the drum and rotates with it in closed, sealed engagement.

The sealing mechanism comprises a dished or frusto-conical closure ring 40 having a flanged portion 41 abutting at substantially right angles a wear ring 42 surrounding the drum opening. Since there is some relative movement between these two abutting surfaces, caused by the fact that closure ring 40 when brought into engagement with the drum may not be engaged sufficiently to cause rotation, a replaceable wear ring 42' may be skip welded or otherwise removably secured to the flange of the closure ring in position to engage the end of the drum. This ring may well be constructed in two semi-circular parts so that either may be replaced independently of the other for ease in assembly and also in the event wear should be localized on one of the parts.

The inner periphery of the dished closure member 40 carries a channel 43 opening toward the charging passageway, said channel comprising two members 44 of Z-shaped cross section, with abutting surfaces 45 secured by a plurality of bolts 46 to the closure ring. Bolts 46 which are angularly spaced also support a bearing ring 47 spaced axially outwardly from the channel just described. As illustrated herein bearing member 47 is an integral annular casting having sleeve portions enclosing bolts 46, the sleeve portions being spaced angularly about the drum axis as hubs in the manner and for the purposes set forth in Patent No. 2,281,820 to Charles F. Ball. As explained in said patent, should any grout work through the seal, it will escape to the ground and not enter the bearing members.

Bearing portion 47 has an inner annular face and an outer, radial face for engagement with an annular member 48 of L-shaped cross section surrounding and secured to the lower portion of the hopper. The inner annular bearing surface is provided with two annular grooves 49

for reception of grease, the bottom of these grooves communicating with a recess in the outer radial bearing face for the transmission of the lubricant. The radially flanged portion of L-shaped member 47 is secured to a skirt plate 50, the latter being mounted on the hopper and secured thereto as by the weld 51. Plate 50 is recessed as at 52 for insertion of a grease fitting 53 which extends through it and L-shaped member 48 in alignment with the groove in the outer radial face of bearing member 47.

Referring specifically to Figure 3, it will be seen that L-shaped member 48 carries on its outer annular face, packing elements arranged for retention in channel 43, which as previously described, is carried by the closure plate 40. The packing element assembly comprises a ring member 54 which fits snugly around the rim or cylindrical portion of L-shaped member 48 and a pair of radially spaced bands 55 of normally flat but flexible material, the medial portion of the inner band contacting and flexing about the convex outer surface of ring 54. The two bands 55 are spaced slightly apart by a spacer ring 56, which may also be of flexible or yielding material, the bands, spacer ring and supporting ring being retained in assembled relation by a plurality of radially spaced rivets 57 extending through these elements and located in counterbored holes 58 in supporting ring 54. These same counterbored holes 58 may be employed to lock ring 54 against axial displacement or rotation with respect to its supporting member 43, in which case tapped holes are arranged in member 48 and cap screws can be inserted through appropriately disposed apertures in the walls of the hopper and threaded through member 48 till the ends of the screws extend into holes 58 to lock the supporting ring 54 in its desired position.

The width of the retaining channel 43 which is associated with the closure ring 40 is slightly less than the width of flexible bands 55 and consequently when the bands are inserted in the channel they assume an arcuate form with their end edges tightly pinched against the inner sides of the channel, the direction of flexing being such as to oppose and prevent the passage of material from the inside of the hopper through the seal which is thus formed between the packing bands and the channel. As previously stated, when the hopper is moved into charging position, closure plate 40 rotates with the drum due to frictional engagement, whereas bands 55 remain stationary since they are associated with the hopper which is held against rotation by the actuating arms 37.

To further inhibit passage of concrete through the seal and to lubricate the rotating sealing surfaces, provision is made for packing the space between the outer of the sealing bands 55 and the web of channel 43 with a concrete setting inhibitor and lubricant. This is accomplished by providing a grease fitting 59 which communicates through a hollow tube 60 with a specially constructed cap screw 61 having provision for receiving tube 60 and itself having a hollow portion for transmitting grease into opening 58. In this instance the rivet 57 which retains the packing assembly is hollow so that the grease may be forced back of the seal and will then work in opposition to material trying to pass the seal. One or more such grease fittings and hollow rivets may be employed, it being understood that the remaining rivets are solid so that the only

place the grease may pass out of the channel is through the space between the edges of the bands and the inner walls of the channel. Cap screw 61 may also function as a retaining device for ring 54 with its head end accessible from the inside of the hopper the same as the other retaining cap screws.

The provision of several bands 55 provides a plurality of sealing surfaces and with lubricant constantly present under pressure in the reservoir at the base of the channel 43, a very effective seal is obtained. The presence of grease in this reservoir will also inhibit the setting of concrete in the seal should concrete work past the opening between the end of the inner flange of channel 43 and the angle ring 48 and hence past the bands 55.

Since the hopper is under pressure to maintain sealing engagement with the drum, movement of the hopper toward the left as shown in Figure 1 will cause sealing bands 55 to be pressed into closer contact with the inner flange of the channel 43, thereby making more effective the seal which is relied upon to oppose the initial effort of the concrete to escape. Furthermore as wear occurs between the radial face of the bearing member 47 and the L-shaped supporting ring, the hopper will move also toward the left, thereby improving the seal and compensating in effect for such wear as may take place on the edges of the sealing bands.

While I have disclosed packing members 55 as separate bands spaced by a separate member 56, they may well be molded as one piece. Similarly instead of two such bands being employed, one band or even more than two bands might be substituted without departing from the spirit of the invention. I have found that belts made of canvas cut at a bias provide an end grain which is highly satisfactory due to the fact that the threads run diagonally across the belt and thereby provide greater resistance to wear at the edges which contact the inner sides of channel 43.

For supporting the drum 11 there is provided a rim or track 63 spaced a short distance ahead of the charging and discharging opening 13 and surrounding the conical discharge portion of the drum. This rim or track is adapted to run on rollers mounted on the frame of the mixer which therefore provide a bed for the drum and support the rear portion thereof. Reference may be made to aforesaid Ball Patent 2,265,751 for a showing of the disposition of said rollers with respect to the frame. Since the drum is mounted for rotation about an inclined axis, the rollers exert axial as well as radial thrust on the track and difficulty has been experienced in providing a track which can be so secured to the drum that it can withstand the strains imparted in the regions where it is connected to the drum, said strains being especially severe when the mixer is transported over rough or irregular roads. I have found that by spacing track 63 a slight distance outwardly from the wall of the drum and connecting only the medial portion of the track to the drum wall by the use of a supporting ring or web 64 of sufficiently light section that the web may flex or yield under variations in pressure on the track that these difficulties can be largely overcome and the welds provided they are sufficiently limited in area so as not to build up the section when securing web 64 to the drum 11 will stand up better under actual service conditions. Further-

more, due to the less rigid construction employed, full contact is obtained between the track and the drum rollers.

The supporting means for the drum constitutes the subject matter of applicant's copending application Serial Number 753,333, filed June 7, 1947.

From the foregoing it should be clear that there is provided an improved arrangement for supporting the mixing drum and the charging instrumentalities associated therewith whereby the charging element may be disposed concentrically with respect to an axial opening in the end of the drum. This is accomplished by a pilot shaft mounted on the true axis of the drum through the provision of hubs having a slightly larger aperture than the diameter of the shaft to compensate for eccentricity caused by manufacturing and assembly operation, said shafts coacting with a collar journaled on the shaft and secured to the hub after the shaft has been aligned with the true axis of the drum. In order to support the charging hopper adequately and resist the bending movement which it exerts on the pilot shaft, a pair of axially spaced hubs are provided with spokes rigidly secured thereto, which spokes comprise telescopic members which are adjustable prior to welding to locate the shaft axially of the drum. The outer ends of the spokes are rigidly secured to the blade flanges, said ends being bevelled in order that they may abut against the inclined outer surfaces of the blade flanges.

Proper alignment between the charging hopper and the drum improves the sealing relation which is provided between their contacting surfaces and enables closure ring 40 to rotate with the drum and insures that bearing pressure will be transmitted through bearing member 47 which is disposed between the charging hopper and the rotatable closure ring. As previously described sealing bands 55 are pressed into sealing contact with the aforesaid closure ring, the closure ring being supported through bearing 47 independently of the sealing bands, whereby the sealing members are maintained in floating relation and protect the bearing against abrasive action which would result if concrete could come in contact therewith.

The invention having been described what is claimed is:

1. In a concrete mixer having a rotatable mixing drum provided with an axial opening at one end and a non-rotatable charging hopper arranged to feed material through said opening, a rotary seal disposed between the hopper and the drum comprising a flexible band medially supported so that its edges may flex and a retaining channel rotatable with respect to said band, the web of said channel being concentric with said band and said channel being of width less than the width of said band whereby the edges of the band are flexed into arcuate shape while retained by the flanges of the channel, the tendency of the band to straighten while so flexed causing pressure to be exerted against the channel by said edges and opposing the passage of material through the seal.

2. A seal for concrete or like material between two concentric members one of which is rotatable with respect to the other, comprising a ring secured to one of said members, a flat band of flexible material substantially wider than said ring having its medial portion secured to said ring, and an annular channel rotatable with the other member

member and arranged to retain the aforesaid band, with its web portion concentric with said band, the width of said band being greater than the width of said channel, whereby the edges of the band are flexed into arcuate form when pressed into the channel and each edge of the band forms sealing contact with the inner side of the flanges of the channel so that the material must pass seriatum through the sealing surfaces before it can escape through the seal.

3. In a concrete mixer having a charging chute held in non-rotating position and a rotating mixer drum with an opening at one end for receiving materials fed through said chute, a seal disposed between said chute and said drum comprising a ring associated with the chute, a normally flat band of flexible material mounted on said ring, an annular spacer element disposed between the medial portion of said band and the outer surface of said ring, a retaining channel rotatable with said drum having its open end facing said ring and the inner sides of its flanges contacted by the edges of said band and a hollow tubular member extending through said ring and said band for transmitting lubricant into the space between the band and the web of said channel.

4. In a concrete mixer, a rotatable mixing drum having an axial opening at one end and a charging device cooperating with said opening, a shaft axially disposed with respect to said drum and extending through said opening to slidably mount said charging device, a spiral blade mounted in the drum extending to said opening, said blade having a carrying lip formed at an obtuse angle to the blade, the surface of said lip being radially spaced from the axis of the drum, a hub supporting said shaft, a spoke comprising two parts telescopically arranged with one end bevelled to abut against said lip and the other end locating said hub axially with respect to the drum, and means securing said telescopic parts against telescopic movement after location of said hub as aforesaid.

5. A seal as set forth in claim 2 comprising a plurality of such bands arranged concentrically and radially spaced from each other.

6. In a concrete mixer having a rotatable mixing drum and an axial opening at one end thereof, a shaft disposed axially of said drum and adapted to support instrumentalities concentrically associated with said opening, a fabricated assembly for supporting said shaft and permitting its accurate alignment with the drum axis comprising a hub having an opening larger than said shaft and through which the shaft may be extended, supporting means connected to the drum including at least one spoke made up of telescopic members, means securing the telescopic members in predetermined position, and a collar having an aperture sufficient to just contain said shaft, said collar being secured to said hub and locating the shaft on the true axis of the drum.

7. A seal between two members one of which is rotatable with respect to the other, comprising an annular member, a ring mounted on said member, a flat band of flexible material substantially wider than said ring having its medial portion secured to said ring, and an annular channel rotatable with the other member and disposed to retain the aforesaid band, the edges of the channel flanges being in close contacting position with respect to said annular member, and the web of said channel being concentric with said band,

the width of said band being greater than the width of said channel, whereby the band is flexed into arcuate form when retained in the channel with the concave side of the band on the same side as the open side of the channel.
